(57) **CLAIM**

The ornamental design for the bed, as shown and described.

DESCRIPTION

FIG. 1 is a perspective view of a bed in accordance with the present invention in which only a portion of the surface treatment is illustrated, it being understood that the surface treatment covers the entire indicated area;

FIG. 2 is a front view of the bed of FIG. 1 without the surface treatment being illustrated;

FIG. 3 is a top view of the bed of FIG. 1 without the surface treatment being illustrated, the bottom view and back view of the bed are not illustrated as they form no part of the present invention;

FIG. 4 is a right side view of the bed of FIG. 1 without the surface treatment being illustrated, the left side view being a mirror image thereof;

FIG. 5 is a perspective view of a second embodiment of the bed in accordance with the present invention;

FIG. 6 is a front view of the second embodiment of the bed, the back of the second embodiment of the bed is not illustrated as it forms no part of the present invention;

FIG. 7 is a top view of the second embodiment of the bed, the bottom of the second embodiment of the bed is not illustrated as it forms no part of the present invention; and, FIG. 8 is a right side view of the second embodiment of the bed, the left side view being a mirror image thereof.
